SPARK PLUG

Melville F. Peters, Beltsville, Md., and John Ellsworth D. McCarty, Jackson Heights, N. Y.; said McCarty assignor to The Firestone Tire & Rubber Company, Akron, Ohio, a corporation of Ohio

Application September 13, 1943, Serial No. 502,388

10 Claims. (Cl. 123—169)

This invention relates to spark plugs for internal combustion engines, and more especially it relates to spark plugs adapted to withstand severe temperature changes and high temperatures for long periods of time.

The invention is of especial utility in its application to spark plugs for airplane engines wherein the aforementioned severe service conditions usually obtain. The high heat in spark plugs developed by engine operation is very difficult to dissipate and in some instances, the center electrode becomes hot enough to burn the insulation from the high tension wire secured to the terminal at the upper end thereof, in addition to burning away the sparking end of the electrode. Furthermore, the strains placed upon the porcelain element by the extreme heat may cause the cracking or breaking of the porcelain with resulting loss of compression in the engine cylinder.

The chief object of this invention is to provide an improved spark plug capable of efficient and satisfactory operation under severe service conditions. More specifically, the invention aims to provide in an improved manner for the dissipation of heat in the center electrode; to increase the rate of heat transfer from the porcelain of the spark plug to the metal shell in which it is mounted; to provide means by which the temperature of the spark plug may be controlled; to provide a spark plug construction wherein the maximum mechanical stresses and the maximum thermal gradients occur at different regions of the plug; and to provide spark plug construction wherein unequal or local stresses on the porcelain are obviated. Other objects will be manifest as the description proceeds.

The single figure of the accompanying drawing shows a spark plug embodying the invention, partly in elevation and partly in longitudinal diametric section.

Referring to the drawing, there is shown a spark plug comprising the usual metal shell 10, a porcelain insulator 11 mounted therein, an axially disposed center electrode 12 carried by the porcelain and projecting from both ends thereof, and a ground electrode 13 carried at the lower end of the shell 10 and projecting radially thereof toward the center electrode 12. The center electrode 12 fits snugly in a bore formed in the lower half of the porcelain 11, the upper half of the porcelain being formed interiorly with screw threads to receive a complementally threaded portion 12a of said electrode, the arrangement being such as to provide gas-tight engagement

of porcelain and electrode. The upper terminal portion of the electrode 12 is threaded at 12b to receive the usual nut 14 by means of which a wire (not shown) of the ignition system of a motor may be connected to the plug.

The porcelain 11 is formed exteriorly at its medial region with a circumferential flange or bulge 16, which flange is received within a recess 17 in the metal shell 10, the lower end of said recess being defined by an annular ledge or shoulder 18. The salient feature of the invention is a thin metal girth sheath 19 on the outer face of the porcelain 11, said sheath covering the flange or bulge 16 of the porcelain, and extending above and below the same. The arrangement is such that when the porcelain is operatively mounted in the shell 10, the metal sheath 19 extends somewhat beyond the top of the shell 10, and somewhat below the shoulder 18 therein, the bulge 16 of the porcelain being centrally disposed in the recess 17 of the shell 10. The porcelain is securely held in place in the shell by means of a pair of annular metal gaskets 20, 20 that are snugly received in the recess 17, and have inner circumferential faces shaped complementary to the peripheral surface of the metal-clad portion of the porcelain 11 so as to fit substantially flush thereagainst. The lower gasket 20 rests upon the shoulder 18, and the upper end of the shell 10 is crimped at 21 over the upper gasket 20 so as permanently to secure the elements of the plug in properly assembled relation. The shape of the gaskets 20 is such that they have wedging engagement with the porcelain 11 and the peripheral face of the recess 17.

The ideal composition for the porcelain sheath 19 is a metal, such as platinum, iridium or the like that has the same low thermal expansion as porcelain, but these metals are too rare and expensive to be practical. Accordingly, copper has been selected as most nearly satisfactory since it is a good conductor of heat, is soft enough to yield readily under strain, such as will arise due to differences in thermal expansion, is available in sufficient quantity, and is not expensive. The copper is applied to the porcelain by plating, coating, or other suitable means whereby the sheath is in one piece and without seams. The thickness of the copper sheath affects the heat transfer characteristic thereof, so that in practice the copper plating will be of optimum thickness in view of the function to be performed thereby. The gaskets 20 are of softer metal than the steel of the shell 10, and advantageously may be composed of copper or brass.

In use, the high heat of the center electrode 12 is transferred by conduction to the porcelain 11, thence in order to the metal sheath 19, the metal gaskets 20, and the shell 10, finally being dissipated in the cylinder head (not shown) in which the plug is mounted. The rate of heat transfer from the porcelain 11 is increased many fold over conventional spark plugs since the metal sheath and metal gaskets 20 greatly increase the area of the metal path from porcelain 11 to shell 10. By varying the length and/or the thickness of the sheath 19 it is possible to control the heat of the plug.

The invention also is advantageous in that fewer porcelains will be damaged during assembly of the plugs, and during use thereof. Porcelains commonly are not straight or true due to the process of forming and firing the same. Such porcelains are subject to unequal or local stresses during assembly with the shell, and subsequently due to thermal expansion, and as a result frequently are fractured. Such porcelains when metal-clad according to the invention will not readily fracture since the soft metal sheath will flow and equalize the stresses to which the porcelain is subjected, and also will function to dissipate heat so that the extent of thermal expansion is reduced. Furthermore, the greatest thermal gradients reach their maximum value in the porcelain at the respective ends of the metal sheath 19, whereas the mechanical stresses on the porcelain reach their maximum value in the bulge 16 where the gaskets 20 are urged thereagainst. By having the end portions of the sheath 19 extend beyond the region engaged by the gaskets 20, as shown, the maximum thermal gradients and maximum mechanical stresses are prevented from occurring at the same place.

As indicated in the next preceding paragraph when soft metal is used for the sheath, the metal will flow and equalize the stresses to which the porcelain is subjected due to the porcelain not being straight or true as a result of the method of forming and firing such porcelains. However, an important feature of the invention resides in the fact that the metal plating or sheath of the porcelain makes it possible to straighten or true the plated or sheathed porcelains by a common lathe operation. Ordinarily, of course, such turning or similar operation would be necessary only where a bent or untrue porcelain has been plated with a hard metal. However, it is to be understood that if found desirable the copper plating or sheathing referred to may be machined or turned down to true it to make accurate and intimate contact with the gaskets 20 whereby localized pressures are avoided and the rate of heat transfer of the metal parts is substantially improved since the plated metal or girth sheath 19 contacts the porcelain over an extensive area.

The invention provides in a simple and inex-

pensive manner for improving the efficiency and lengthening the useful life of spark plugs subject to extreme heat, and achieves the other advantages set out in the foregoing statement of objects.

Modification may be resorted to without departing from the spirit of the invention or the scope thereof as defined by the appended claims.

We claim:

- 10 1. A spark plug of the character described comprising a generally tubular metal shell formed interiorly with a circumferential recess, a porcelain insulator positioned axially within said shell and formed intermediate its ends with a circumferential bulge that extends into said recess, metal sheathing on the porcelain covering said bulge and extending above and below the same, and metal gaskets in said shell recess having wedging engagement with the metal sheathing in the region of said bulge.
- 15 2. A spark plug as defined in claim 1 in which the metal sheathing is composed of a soft metal that is readily deformable under stress.
- 20 3. A spark plug as defined in claim 1 in which the metal sheathing is composed of copper.
- 25 4. A spark plug as defined in claim 1 in which the metal sheathing is plated onto the porcelain.
- 30 5. A spark plug as defined in claim 1 in which the metal gaskets are of softer metal than the shell.
- 35 6. A spark plug as defined in claim 1 in which the metal of the gaskets comprises copper.
- 40 7. A spark plug comprising a porcelain insulator for supporting a center electrode, a seamless girth sheath of soft metal on said porcelain, a metal shell formed interiorly with a circumferential recess in which said porcelain insulator is axially positioned, and metal gaskets occupying the remainder of said recess and engaging said sheath to constitute a heat-conducting structure from the insulator to said shell.
- 45 8. A spark plug comprising a porcelain insulator for supporting a center electrode, a seamless girth sheath of copper plating on said porcelain, a metal shell formed interiorly with a circumferential recess in which said porcelain insulator is axially positioned, and metal gaskets occupying the remainder of said shell recess and having wedging engagement with the sheath on said insulator.
- 50 9. A spark plug as defined in claim 1 in which the metal sheathing is of a type having substantially the same low thermal expansion as porcelain.
- 55 10. A spark plug comprising a porcelain insulator for supporting a center electrode, and a seamless girth sheath of metal on said porcelain, said metal having substantially the same low thermal expansion as porcelain.
